HYDRAULIC VALVE MECHANISM

George E. A. Hallett and Leroy W. Shutts, Detroit,
Mich., assignors to General Motors Research
Corporation, Detroit, Mich., a corporation of
Delaware

Application August 5, 1927. Serial No. 210,824

7 Claims. (Cl. 123—90)

This invention relates to hydraulic operating mechanism of the type in which a body of fluid is interposed between an operating and an operated part to transmit movement from the one to the other. The object of the invention is to provide means for automatically venting air which may collect in the chamber and interfere with operation of the mechanism. Essentially, the invention consists in providing more or less continuously open vent, preferably at the highest point in the hydraulic chamber. In its simplest embodiment, the vent may be constituted by a fitting comprising a needle valve which is adjusted so as to be slightly spaced from its seat. Instead of having the vent permanently open, an intermittently open vent may be provided. This may be accomplished by providing an extension on one of the plungers working in the hydraulic chamber, the extension having a sliding fit in an aperture or guide formed in a wall of the hydraulic chamber and being provided with a port uncovered during a portion of its stroke permitting the escape of air and oil from the chamber. In some cases, the port may be dispensed with the extension simply being a sloppy fit in the guide so that air may escape around the plunger. With this construction, the vent is, to some extent, cleared of obstructing matter by the motion of the reciprocating part. The invention likewise embodies an improved design of hydraulic chamber which facilitates machining and enables the device to be produced at smaller cost.

In the drawing, Figure 1 is a vertical section thru a conventional automobile engine showing our improved valve operating mechanism applied thereto. Figures 2 and 3 are sectional views thru slightly different forms of valve mechanism.

Reference character 4 indicates a conventional automobile engine having piston 6, cam shaft 8, push rod 10 and valve 12, the valve being held upon its seat by coil springs 14. 16 indicates a casting secured to the top of the engine block, the casting being provided with a transverse cylindrical bore 18 forming the hydraulic chamber and with intersecting bores 20 and 22, bore 20 receiving plunger 24, and bore 22 receiving plunger 26. The plunger 24 is yieldingly held in engagement with the upper end of push rod 10 by means of spring 28. While this spring is shown mounted within the hydraulic chamber, it may if preferred be located outside of the chamber as between an outwardly extending flange formed at the bottom of the plunger 24 and the under side of the casting 16. To the upper end of the plunger 24 is secured the extension 30 which has a loose sliding fit in aperture or guide 32 formed in the upper wall of the chamber 16. Plunger 26 is yieldingly held in engagement with the spindle of the valve 12 by means of spring 33 shown as of the "rat-trap" type—that is, the spring consists of a strip or wire of spring metal bent to form arms 34 and 36 connected by a loop 38 of one or more turns.

40 indicates an oil reservoir which may extend along the cylinder block and serve for filling any number of hydraulic chambers 18, as desired. Oil from the reservoir 40 is admitted to the chamber 18 thru check-valve 42 carried in plug 44 closing one end of the chamber. A second plug 46 seals an opening in the wall of the reservoir in alignment with the bore 18. The reservoir 40 may be supplied with oil from the crankcase thru conduit 48. 50 indicates a pipe 75 for returning excess oil to the crankcase. A pressure relief valve 52 may be provided in the return pipe.

With the described construction, it is apparent that the chamber 18 may be formed in the casting 16 by drilling the casting from the right-hand end and the bores 20 and 22 may be similarly formed. This provides a cheap construction and, at the same time, makes it possible to have an hydraulic chamber with all its surfaces 80 machined so as to prevent the trapping of air bubbles along the walls of the chamber.

In the operation of this form of device, upward motion of the push rod 10 transmitted thru the plunger 24 results in displacement of the 90 fluid in chamber 18 and consequent forcing of the plunger 26 downwardly unseating the valve 12. During this part of the cycle check valve 42 is forced into engagement with its seat preventing the return of oil to the reservoir but, owing 95 to the loose fit of extension 30 in guide 32, air and oil will be forced out into receptacle 50 which may be in the form of a trough. The oil, overflowing the trough, returns to the crankcase thru the push rod guides. When the high point of 100 the cam moves from beneath the push rod, the oil in the chamber 18 is relieved of pressure and the plunger 20 follows up the push rod under the influence of spring 28. As a consequence, a 105 partial vacuum is produced in the chamber 18 which results in drawing oil into the chamber 18 from the reservoir 40 past check valve 42. The oil in the chamber is thus constantly replenished and on each operating stroke, the oil and contained air collecting in the highest part of the 110

chamber is forced out in the manner described. The fact that extension 30 works in the guide 32 insures that the vent will, at all times, be clear of foreign particles so that passage of air is not interferred with.

In the form shown at Figure 2, the construction of the hydraulic chamber is somewhat simplified and a fixed vent is provided. Here 60 indicates the hydraulic chamber which, as above, is formed by drilling the casting 62 from the right-hand end. The outer end of the chamber is closed by plug 64 containing ball check valve 66. The valve controlled passage 68 provided in the plug and communicating with reservoir 70. The reservoir is supplied with oil from the crankcase thru conduit 72, preferably at a pressure of about 20 lbs. per square inch. Conduit 74 equipped with pressure relief valve 76 provides for the return of excess oil to the crankcase. In this form, the vent is arranged as before in the highest point of the chamber, but takes the form of a simple needle valve 78 set in a position slightly off its seat so as to permit the discharge of oil and air from the chamber 60 into the trough 80. In this form of the invention, the machining of the hydraulic chamber is further simplified and the air vent is free of moving parts.

Figure 3 shows somewhat diagrammatically a further modification. In this form, the bore 90 is closed by a simple plug 92, while the oil reservoir is located at the opposite end of the casting, as shown at 94. The reservoir 94 communicates with the hydraulic chamber 90 through port 95 which is uncovered on the downstroke of the piston 102. Oil is supplied to this reservoir through conduit 96 while pressure relief valve 98 and conduit 100 permit the return of excess oil to the crankcase. Piston 102 is provided with tubular extension 104 working in guide 106 formed in the opposite wall of the chamber 90. The extension 104 is hollow and is provided with an aperture 108 which during the major portion of the operating stroke of the plunger 102 lies within the guide 106 but, during the return stroke and the initial portion of the operating stroke is exposed within the chamber 90 so as to permit the escape of oil and air particles. The piston 102 may be rigidly secured to the valve tappet or may be separate and yieldingly held in engagement with the tappet by means of a coil spring such as shown at 28 in Figure 1. There is thus provided a simple form of mechanically operated

vent for relieving the chamber of its air content. It is understood, of course, that the oil in the reservoir 94 will be maintained at suitable pressure, say 20 lbs., to insure that the chamber 90 is at all times full of oil.

We claim:

1. In hydraulic valve operating mechanism, the combination of an operating plunger, an operated plunger, a body of fluid interposed between said plungers, said operating plunger being provided with an extension guided in an aperture in the wall of said chamber, said aperture and extension cooperating to permit the escape of air.

2. A head for hydraulic valve gear for internal combustion engines provided with a transverse cylindrical socket forming an hydraulic chamber, means for closing one end of said socket, and angularly related bores intersecting said transverse bore for receiving the operating and operated plungers.

3. In hydraulic valve operating mechanism, the combination of an hydraulic chamber, operating and operated members working in the chamber, and a mechanically operated leak for permitting escape of air from the chamber, one of said members comprising a reciprocating plunger and said leak comprising an extension on said plunger guided in an aperture in the chamber wall.

4. In the combination as defined in claim 3, said leak being arranged at the highest point in said chamber.

5. A head for hydraulic valve gear for internal combustion engines provided with a cylindrical socket forming an hydraulic chamber, means for closing one end of the socket, offset passages communicating with said socket, an operating member working in one of said passages, and an operated member working in another of said passages.

6. Hydraulic valve mechanism comprising an hydraulic chamber, operating and operated members working in the chamber, a supply chamber, and a fitting provided with a passage establishing communication between the reservoir and chamber, said fitting being accessible from outside said chambers and readily removable therefrom for replacement or repair.

7. The combination as defined in claim 6, and a valve carried by the fitting for controlling flow through the passage.
